UNITED STATES PATENT OFFICE.

JAMES E. SMITH, OF ST. LOUIS, MISSOURI, ASSIGNOR, BY DIRECT AND MESNE ASSIGNMENTS, TO SMITH AND SEPER COMPANY, OF ST. LOUIS, MISSOURI, A CORPORATION OF MISSOURI.

WHIRLING SEESAW.

1,344,965.

Specification of Letters Patent. Patented June 29, 1920.

Application filed September 26, 1919. Serial No. 326,434.

To all whom it may concern:

Be it known that I, JAMES E. SMITH, a citizen of the United States, residing at the city of St. Louis, in the State of Missouri, have invented certain new and useful Improvements in Whirling Seesaws, of which the following is a specification.

This invention may be constructed either as a toy or as a larger-sized amusement device for the entertainment, for a charge, of visitors at summer gardens and similar places of amusement.

This device is a whirling or rotary seesaw, and combines the up-and-down movement customary in seesaws with a rotary motion upon a central pivot.

In addition, this device is so constructed that the seesaw motion produces the rotary movement.

20 In the accompanying drawings forming part of this specification, in which like numbers of reference denote like parts wherever they occur,

Figure 1 is a top-plan view;

25 Fig. 2 is a side-elevation;

Fig. 3 is a detail on an enlarged scale taken on the line 3—3 in Fig. 1;

30 Fig. 4 is a side elevation showing the means of attachment of a lever to a brace; and

Fig. 5 is an elevation at a right-angle thereto taken on the line 5—5 in Fig. 4.

Any suitable base or central standard may be used, but, as shown in the drawings, 35 the base consists of cross-members 1, surrounded by a platform 2, from which rise posts 3, adapted to support track 4.

Track 4 is provided with notches 5 or the like, adapted to act as resistants against 40 the push of levers 6 and 7.

When one end of the beam 8 of the seesaw is depressed, in the ordinary mode of operation, such depression exerts a push upon lever 6, and, when the opposite end of beam 45 8 is depressed, such depression imparts a push to lever 7.

Braces 9 and 10 are provided at their upper ends with castings 11 and 12, which terminate in plates 13 and 14, having there- 50 through openings 15 and 16, through which passes a spindle 17 that is supported by central standard 18. Thus, braces 9 and 10 are in loose pivotal attachment to standard 18. They are held from rising on spindle 17 by 55 block 19, which contains a socket 20, to re-

ceive spindle 17. The weight of beam 8 and of the passengers in seats 21 and 22 is sufficient to keep block 19 from riding so far up on spindle 17 as to permit the disengagement of plates 13 and 14 therefrom. 60

Block 19 is fastened by screws 23 to depending brackets 24, attached to beam 8.

Beam 8 is preferably provided with a slot 25, in which the tongue 26, extending from seats 21 and 22, is adapted to slide. The 65 said tongues 26 are fastened by screws 27 to the said seats 21 and 22, and are provided with foot-rests 28, extending upwardly therefrom. They are held in slot 25 by plates 29, held thereto by thumb-screws 30. 70 The beam 8 may be made of a solid member containing a slot 25 or an opening in lieu thereof, or it may be composed, as shown in the drawings, of separate pieces or strips 31, fastened together by cleats 32 and 33, 75 member 34 and block 19.

The entire construction may be made of metal, if desired, in which case the castings 11 and 12 would be dispensed with, and the said parts, together with plates 13 and 14 and 80 the body of braces 9 and 10 and the parts at their opposite ends may be formed integral.

The lower ends of braces 9 and 10 are formed with three-sided clasps 35. The wings 36 ride respectively on the outside 85 and inside of the member bearing the notched track 4, while the main body 37 of the said clasps 35 rides upon the notched track 4, being provided with a lip 38, for engagement with the notches 5. 90

Levers 6 and 7 are pivoted, at 39 and 40 respectively, in bifurcated brackets 41, attached to the beam 8.

When one end of beam 8 is depressed in seesawing, lip 38 on clasp 35, borne by the 95 said lever 6, engages with an adjacent notch 5 on track 4, and the harder the impulsion downward of that end of beam 8 the harder the push that the said notch 5 gives to the end of lever 6, thereby causing beam 8 to 100 rotate in the direction in which the said push occurs. When the opposite end of beam 8 is depressed, lip 38, on clasp 35, at the end of lever 7, pushes against an adjacent notch and adds further impulse to the 105 rotary motion of the beam 8, and thus, while seesawing up and down, the beam 8 simultaneously revolves on standard 18. A lip 42, on clasp 35, is pivoted at 43 to another clasp-member 44, which is pivoted by 110

pin 45 to the lower end of each of the levers 6 and 7.

In practice, when the seesaw begins to dip, the lip 38 immediately takes hold of 5 a notch 5. This permits a complete dip.

It will be noted that, by reason of screws 23, the beam 8 is in pivotal relation to the block 19 and that, by reason of block 19 being mounted on spindle 17, the beam 8 is 10 adapted to rotate on standard 18. Beam 8 is thus in double pivotal relation to standard 18.

Having thus described this invention, I hereby reserve the benefit of all changes in 15 form, arrangement, order, or use of parts, as it is evident that many minor changes may be made therein without departing from the spirit of this invention or the scope of the following claims.

20 I claim:

1. The combination of a central support, a circular track thereabout, braced means movable over the track and engageable therewith, at times, a beam in double pivotal 25 relation to the support, and levers pivoted to the beam and to said means.

2. The combination of a base, a notched track supported thereby, a central standard, a beam in pivotal connection with the said 30 standard, braces in pivotal connection with the said standard, levers in pivotal connection therewith and with the said beam, and means in connection with the said levers adapted to engage and hold in the notches in 35 the said track.

3. The combination of a central support, a track encircling the same and having notches therein, a beam in double pivotal relation to the said support, a brace extending therefrom and having a notch-engaging lip, a lever extending from the said beam, and pivotal connection between the said lever and the said lip.

4. In a device of the character described, 45 the combination of a track, a central support, a beam, a block supported from the said beam, a pivotal connection between the said block and the said beam, a pivotal connection between the said block and the said support, a brace in pivotal connection with 50 the said support and extending to the said track, a lever in pivotal connection with the

said beam, and a pivotal connection between the said lever and the said brace, the said pivotal connection being adapted to permit 55 movement in two directions.

5. In a device of the character described, the combination of a track, a central support, a beam, a block supported from the said beam, a pivotal connection between the said block and the said beam, a pivotal connection between the said block and the said support, a brace in pivotal connection with the said support and extending to the said track, a lever in pivotal connection with the 60 said beam, and a pivotal connection between the said lever and the said brace, the said beam having a slot and seats mounted thereon having members adapted to slide in the 65 said slots.

6. In a device of the character described, the combination of a track, a central support, a beam, a block supported from the said beam, a pivotal connection between the said block and the said beam, a pivotal connection between the said block and the said support, a brace in pivotal connection with the said support and extending to the said track, a lever in pivotal connection with the 70 said beam, and a pivotal connection between the said lever and the said brace, the said beam having a slot and seats mounted thereon having members adapted to slide in the 75 said slots.

7. The combination of a central support, a track encircling the same, a beam in double pivotal relation to said support, a brace extending from the support provided with an 80 engaging portion, a lever extending from the beam, and pivotal connection between said lever and said engaging portion.

8. The combination of a central support, a circular track thereabout having notches in its upper side, means movable over said track and engageable with the notches therein, at times, a beam in double pivotal relation to the support, and opposed levers pivoted to 85 said beam and said means.

In testimony whereof I hereunto affix my signature.

JAMES E. SMITH.
